ELECTRICAL SWITCHING DEVICE

Hubert Mackenzie Salmon, Fareham, England,
assignor to Graviner Manufacturing Company
Limited, London, England

Application July 2, 1934, Serial No. 733,520
In Great Britain July 28, 1933

17 Claims. (Cl. 200—52)

This invention relates to electrical switching devices of the kind in which a pendulum controls the operation of the switch contact elements.

An object of the invention is to provide an electrical switching device for use upon vehicles and crafts in which the switch contact elements are actuated by a comparatively powerful spring under control of a pendulum subject only to small reaction.

10 Another object of the invention is to provide a switching device in which the switch contact elements are actuated by a spring operated member interconnected to a pendulum by a pivotally mounted lever element.

15 A still further object of the invention is to provide an automatically operable switching device adapted to disconnect all electrical circuits in a vehicle or craft in an accident.

With these and other objects in view, the invention will be better understood from the following detailed description taken in connection with the accompanying drawings wherein:

20 Figure 1 shows an electrical switch controlled by a pendulum together with a diagrammatic representation of a circuit controlled by the switch.

Figure 2 shows a slightly different form of switch mechanism to that shown in Figure 1.

25 Figure 3 shows a mechanism in which the pendulum is of a different form from that shown in Figures 1 and 2.

30 Figures 4 and 4a show arrangements of mechanism employing a multiple catch arrangement in side elevation and front view.

35 Figures 5 and 5a show a still further modification of a pendulum device.

30 Figures 6 and 6a show respectively side elevation and front view of a mechanism and switch device arranged to be locked in operated and non-operated positions.

40 Figures 7 and 7a show respectively side view and front elevation of an instrument comprising a pendulum controlled switch device mounted in a protecting case.

45 Fig. 8 is a vertical sectional view of my device taken on the line 10—10 of Fig. 9, showing the switch mechanism in unset position, with ignition circuit open.

50 Fig. 9 is a vertical sectional view taken on the line 11—11 of Fig. 8, showing the switch spring contact elements, and operating cams and levers.

55 Fig. 10 is a vertical sectional view similar to Fig. 8, with the switch mechanism set and the ignition circuit closed.

Fig. 11 is a vertical section taken on the line 13—13 of Fig. 10.

Fig. 12 is a horizontal sectional view taken on line 14—14 of Fig. 10, showing details of the switch mechanism, and

Fig. 13 is a detail of the arcuate sector cam which engages the pendulum cam.

Referring to Figure 1 of the drawings, numeral 2 represents a pivotally mounted pendulum comprising a mass 3 and a mushroom shaped head 4, the pendulum being mounted by means of a ball 5 supported in a socket device 6 carried by bracket 7 itself secured to a mounting plate 8 of the device.

The switch mechanism comprises a rigid contact element 9 provided with a current conducting contact engaging a similar contact carried by the leaf spring contact element 10. In addition a further rigid contact element 11 is provided with a contact adapted to be engaged by a similar contact carried by another leaf spring 12.

The switch is so arranged that it is adapted to be operated by a leaf spring 13, sufficiently powerful to actuate springs 10 and 12, but normally engaged by the toe 14 of a lever device 15 carrying 25 at its other end a member 16 adapted to engage head 4. The lever 15 is pivotally mounted at 17 and is provided with a heel 18, the arrangement being such that spring 13 is normally retained in the position indicated in Figure 1, but is released when the mass 3 of the pendulum is displaced, for example, due to the tilting of the mechanism or as a result of exceedingly violent impact.

When spring 13 is released it opens the normally closed contact points carried by elements 9 and 10 and closes the contact carried by elements 11 and 12 and the switch remains in this position until operating handle 19 is pressed downwardly to a sufficient extent to force the end of 40 spring 13 into engagement with the heel 18 of lever 15, whereby the element 16 is lifted clear of head 4 so that pendulum 2 can assume its normal position indicated in Figure 1.

Figure 1 shows how the switch controls the 45 electrical supply resources on a vehicle or craft which sources comprise battery 20 and generator 21. Normally one lead is taken from the battery output terminal to the electrical system on a 50 vehicle including the lamps and ignition coil as well as various electrically operated devices. This lead is cut and connected to a connector 22 itself connected by leads to normally closed contacts 9 and 10 in such a manner that all cur- 55

rents supplied by battery 20 except to the self-starter flow over the normally closed contacts.

The generator 21 has its output terminal connected to one of elements 11 or 12, the other being connected to earth or to the other terminal of the generator, the arrangement being such that when spring 13 operates spring contacts 10 and 12, the generator is short circuited.

As will be noted the lever 15 is provided with toe and heel parts 14 and 18 so arranged that the spring 13 engages the lever in a plane parallel and closely adjacent to that through the center of the lever 15 so that, although the tension of spring 13 may be quite considerable, the force supplied by element 16 to the head 4 of the pendulum 2 is comparatively small.

Referring to Figure 2, the lever 15 controls a knife blade switch comprising blade 23 and fixed contacts 24, a projecting catch 25 being engaged by toe 14 of the lever 15, a helical spring 26 actuating the switch and a projecting member 27 serving to reset the mechanism after actuation as a result of an accident or the like.

Referring to Figure 3, this figure shows a slightly differently shaped lever 15 and an operating member 28 actuated by a helical spring adapted to actuate a contact assembly substantially as indicated in Figure 1. The pendulum device shown in Figure 3 however, differs substantially from that described in Figures 1 and 2 and comprises a cam device 29 carried by arms 30 pivotally mounted at 31 upon a collar or the like 32, itself mounted to pivot or rotate upon a pin or the like 33. The element 16 of lever 15 normally rests upon cam 29 and if the device is turned sideways the cam will move away from element 16 whereby the lever will be released when the pendulum attains a predetermined angular displacement depending upon the length of cam 29.

In the case where the mechanism shown in Figure 3 may be subject to impact in a forward direction the cam 29 will move forward in a forward direction causing release of the lever 15, with resultant operation of the switch.

The contactor 28 is mounted upon a spindle provided with hand operated means so that upon rotation against the action of the operating helical spring the catch 28 will engage heel 18 of lever 15 and bring element 16 into a position in which the pendulum and cam 29 assume the normal position indicated in Figure 3.

In Figure 4, is shown a modification of the lever arrangement in which toe 14 of lever 15 does not engage the switch controlling element directly but engages the long arm 35 of a lever 36 having a toe 37 engaging the switch controlling element 38, a heel 39 being provided upon lever 36 for effecting restoration to normal of the mechanism. The switching device comprises a rotatably mounted drum 40 provided with conducting segments 41 and a contacting brush element 42. The switch may be arranged to open or close the circuit as desired but the drum is actuated by a helical spring 43. The pendulum device takes the form of a flail 44 and lever 15 is provided with a cam 45 engaging a cam shaped portion 46 upon pendulum 44. The pendulum is pivotally mounted at 47 upon a stud or the like 47 itself rotatably mounted in a supporting plate or the like 8.

As will be observed, the point of engagement between lever 15 and the pendulum of Figures 3 and 4 is vertically below the point of support of the pendulum. The shape of cams 29 and 45 is

such that the pendulums when rotating angularly do not effect appreciable movement of lever 15, but the shape of cam 29 and cam 46 is such that when the pendulums move in a forward direction, a movement against the action of the switch actuating springs is effected and the angles of these cam elements are so arranged that the pendulums do not release unless the device is subject to impact of considerable violence.

In Figures 5 and 5a is shown a modified form of the pendulum comprising a mass 48 carried by arms 49 supported by a pivot support 50, the arms 49 forming a cam 51 adapted to engage the element 16 of lever 15, the arrangement being such that upon sideway angular displacement of the pendulum the element 16 is released from the cam 51 when the angle of displacement attains a predetermined value and in the case of impact in a longitudinal direction the mass 48 swings forward or backwards whereby element 16 is again released from cam 51 thus enabling lever 15 to release the switch controlling element.

In Figures 6 and 6a is shown a form of mechanism in which means are provided for operating the contact assembly so as to disable the electrical system upon a vehicle by means such as a key the device thus being capable of preventing unauthorized operation of a vehicle.

The pendulum and lever arrangement are practically identical to those described in connection with the previously described figures, and the contact assembly is that shown in Figure 1 except that spring 13 is mounted adjacent the spring assembly and is adapted to effect actuation thereof by an extension 13a. The means for actuating the switch assembly comprises a rotatably mounted shaft 52 provided with a projecting arm 53 adapted to operate springs 10 and 12 when the shaft is rotated in an anti-clockwise direction. A further arm 54 carried by the shaft serves to engage spring 13 to restore the same into set position in engagement with the toe 37 of lever 36.

In order to ensure correct positioning of the shaft 52, a cam 55 is mounted thereon and is adapted to be engaged by a spring 56 secured to the mounting plate 8 of the instrument.

When the cam is shaped as shown the shaft has two normal positions of 90° angular displacement, and in the normally set position the arms 53 and 54 are so disposed that they do not prevent operation of the device in case the lever 15 should be released by the pendulum.

The shaft 52 may be mounted by bracket elements fixed on the plate 8 and provided with tubular extensions 57 housing split sockets 58 to which the shaft 52 is secured. In order to prevent unauthorized operation of shaft 52 a spring 59 mounted upon tubular extensions 57 is adapted to engage the slot in sockets 58 from which it must be ejected by means of a key 60 which may have slots provided therein adapted to engage pins disposed in the slot in sockets 58 so as to prevent insertion of keys other than those intended to operate the mechanism. The tubular extension 57 and socket 58 terminates against the side of the enclosing casing or cover for the mechanism through which the key hole is accessible and to operate the mechanism by means of the key this is inserted into the keyhole and forced in so as to lift the spring 59, after which the key and shaft 52 can be turned until spring 56 drops into engagement with the appropriate indent in cam 55 in which position the springs 75

10 and 12 open the battery circuit of the car and short circuit the dynamo and disable the high tension system.

5 A spring 61 also mounted upon tubular extension 57 is adapted to engage the slot in the socket 58 when this has been rotated 90°, and upon withdrawal of the key this spring locks the shaft 52 and the switch mechanism in the operated position.

10 Figures 7 and 7a show a practical embodiment 15 of the invention in which a switch mechanism comprising a contact assembly and automatically operable release mechanism is mounted in a protective casing so as to be capable of being mounted for example under the bonnet of a motor car. Electrical leads are provided from the instrument to the battery and dynamo as well as to the high tension magneto if such is provided upon a car, and an additional earth connection is provided 20 from the instrument to effect the appropriate circuit changes.

Referring to Figure 7, numeral 70 indicates 25 the bottom of a protective casing, 71 being the top thereof capable of being secured to the bottom in any suitable manner. The mechanism of the instrument is mounted upon a mounting plate 73 carried by a suitable number of posts 74 secured to the casing bottom 70. The pendulum 75 is provided with a central cam surface 30 76 and is suspended from a support 77 by means of extending lugs which engage a pin 78 mounted in support 77 in such a manner the pendulum is free to swing in planes at right angles to plate 73. The support 77 is carried by a stud 79 fixed 35 to plate 73 in such a manner that it is capable of rotation in a plane parallel to plate 73. The cam 76 engages a triangular arc shaped cam 80 carried by lever 81 pivotally mounted by pin and bracket means upon plate 73. Lever 81 is provided with toe 82 and heel 83 which are engaged 40 by the long arm of a lever device 84 pivotally mounted by pin and bracket means on plate 73.

The lever 84 is provided with toe 85 and heel 45 86 adapted to engage a cam device 87 fixed upon a spindle 88 mounted by a pair of brackets upon plate 73 so as to be capable of rotation but fixed against endway displacement, a resetting handle 89 being secured to an extension of shaft 88 projecting through the protective casing. A helical spring 90 is carried by shaft 88 and arranged to 50 rotate the shaft in a clockwise direction when cam 87 is released by lever 85. The contact assembly comprises fixed contact elements 91 and 92 and spring contacts 93 and 94. The cam 87 is provided with a projecting stud or pin 95 carrying 55 an insulating sleeve adapted to engage spring contacts 93 and 94, the arrangement being such that spring 93 is held in a normally open position as shown in Figure 7, but upon release of cam 87 by lever 84 the stud 95 is rotated until it engages a stop 96 which is connected to a terminal which in its turn may be connected to a high tension magneto if such is employed upon a vehicle or craft whereby the same is 60 switched off when the instrument operates.

Stop 96 is insulatingly supported from mounting plate 73 and is provided with binding post 113. The contact assembly is supported by a stud 114 attached to mounting plate 73. The 65 stud 114 is advantageously of metal and forms part of the switch circuit, and is electrically connected to mounting plate 73. Binding post 120 is attached to stud 114. Shaft 88 is journaled in a pair of spaced supporting plates 116, 75 117, which are attached to mounting plate 73.

The insulating sleeve on stud 95 permits spring 93 to close its contact with the contact upon element 91 and subsequently the spring 94 is forced away from engagement with contact 92 whereby the circuit over these contacts is opened. 5

When the instrument of the present invention is employed upon a vehicle, electrical leads are taken from the battery so that all the current supplied by the battery to the electrical system except the self-starter is normally flowing over 10 contacts 92 and 94. Contact 91 is connected to the dynamo output terminal and contact 93 is connected to the instrument which is connected to earth. When the instrument operates it will be observed that contacts 91 and 93 close before 15 contacts 92 and 94 are opened, this has been found desirable in practice as the dynamo is disabled before the battery circuit is open, whereas liability to damage the electrical devices and lamps exists if the battery circuit is opened 20 before the dynamo is put out of action.

When the instrument is employed upon a vehicle it is mounted so that the pendulum hangs vertically downwards, centrally over cam 80, and when the vehicle is overturned or when it attains an angle of approximately 45° the cam 76 25 disengages cam 80, and, as a result of the action of spring 90, lever 84 turns in an anticlockwise direction as shown in Figure 7 due to the disengagement of toe 85 with cam 87, and lever 81 30 turns in a clockwise direction due to the disengagement of the long arm of lever 84 with toe 82, and as soon as cam 76 releases cam 80 the lever 81 releases lever 84 and this therefore releases cam 87 which is rotated so as to effect 35 closure of springs 91 and 93 and opening of contacts 92 and 94 before coming into contact with the stop 96 whereby this element is connected to earth. The radius of the cam 80 may be struck from the center of pin 79 so that no movement 40 of lever 81 is produced when the pendulum rotates in a plane parallel to plate 73. Alternatively, the radius may be struck from slightly above the center of pin 79 in which case a slight lift of the cam 80 and lever 81, against the action 45 of spring 90, is produced when the pendulum is displaced from its normal central position and this arrangement tends to retain the pendulum in a central position.

In the case where a vehicle is subject to impact, 50 the pendulum 75 moves forward owing to its inertia and cam 76 is caused to lift cam 80 and the long arm of lever 81 against the action of spring 90 to a predetermined extent so as to prevent release in case of a minor impact, for example, when the brakes of a vehicle are suddenly applied or when a slight impact with another vehicle or an obstacle takes place which is not likely to cause serious injury to the driver or damage to the vehicle. The inclination of the 55 cam 76 is however, such that in the case of a violent impact release of lever 81 takes place without fail. The inclination of cam 76 as indicated in Figure 7, is 45° and this has been found to be suitable for practical purposes. 65

The casing comprising parts 70 and 71 is adapted to be mounted upon a vehicle, for example, under the bonnet, and, to facilitate mounting, a pair of lugs or the like 118, 119 are secured to the casing bottom whereby the instrument may be 70 secured in a horizontal position with the part 71 of the casing pointing in the direction of travel of the vehicle.

Electrical leads 100 soldered or sweated to tags 98 upon the contact assembly and secured by 75

clamping devices 99 to the bottom of the casing are provided for connection to the electrical system upon a vehicle or craft.

In the case of switch devices for use on aeroplanes it is desirable that cams 45 and 80 are shaped somewhat as indicated in dotted lines in Figure 4a so as to tend to retain the pendulum in normal position although the instrument is turned sideways or upside down. In order to enable the mechanism to be reset, helical springs 840 and 810 may be provided upon the pivot spindles of levers 34 and 31, Figure 7, tending to rotate the same in a direction to effect disengagement, also a helical spring 730 or the like 10 may be attached to the pendulum 75 so as to tend to retain the same in its normal position, the spring being capable of sufficient extension to effect release in case of impact. When a spring 730 is attached to pendulum 75, the cam 80 may 15 be shaped as shown in Figure 7a as the spring prevents disengagement between cams 76 and 80 except in the case of violent impact. It is of course to be understood that the various parts of the device may be designed and constructed in 20 various other ways, and the various mechanisms arranged in other combinations than illustrated, and therefore I do not wish to be limited in any manner except as set forth in the following claims.

Having thus fully described my invention, what I claim as new and desire to protect by Letters Patent is:

1. A switch for rendering inoperative the electrical circuits of a vehicle upon a condition of collision or the like, comprising: a plurality of electrical contact elements, spring-biased means for maintaining said contact elements in contact under normal conditions, spring means effective to oppose and overcome said last-mentioned means to open said contact elements, latch means for maintaining said last spring means retracted and inoperative, pendulum means associated with said latch means and effective to release the same upon the occurrence of an abrupt acceleration or deceleration of the vehicle, said spring means being provided with a manual positive control operable with a single movement to reset said contact elements in closed position when said pendulum means has returned to normal position.

2. A switch for rendering inoperative the electrical circuits of a vehicle upon a condition of collision or the like, comprising: a plurality of electrical contact elements, means for maintaining said contact elements in contact under normal conditions, means effective to overcome said last-mentioned means and open said contact elements, latch means for rendering said contact opening means inoperative, and pendulum means having a cam element normally in positive locking abutment with said latch means but displaceable to release said latch means upon a swinging of the pendulum occasioned by an abrupt acceleration or deceleration of the vehicle.

3. A switch for rendering inoperative the electrical circuits of a vehicle upon a condition of collision or the like, comprising: a plurality of electrical contact elements, means for maintaining said contact elements in contact under normal conditions, means effective to overcome said last-mentioned means and open said contact elements, latch means for rendering said contact opening means inoperative, pendulum means associated with said latch means and effective to completely release the same upon the occurrence

of an abrupt acceleration or deceleration of the vehicle, and manually operable latch-resetting means for reclosing said electrical contact elements.

4. A switch for controlling the electrical circuits of a vehicle upon a condition of collision or the like, comprising: a plurality of electrical contact elements, means for normally maintaining at least one pair of said contact elements in closed-circuit relationship, means for normally maintaining another pair of said contact elements in open-circuit relationship, means effective to oppose and overcome each of said two last-mentioned means and invert the normal contact positions, latch means for rendering said contact-inverting means ineffective, and pendulum means associated with said latch means and effective to release said latch means upon the occurrence of an abrupt acceleration or deceleration of the vehicle.

5. An electrical switching device for rendering inoperative the electrical circuit of a vehicle upon a condition of collision or the like, comprising a plurality of electrical contact elements, a spring actuated member electrically independent of said contact elements for actuating said contact elements, a lever, a pivotal support for said lever, said pivotal support being attached to said lever at a point along the length thereof to divide said lever into two sections of uneven length, means formed in the shorter of the two sections of said lever for engaging said spring member and holding said member under tension, means engaging the free end of the other of said sections for tripping said lever and releasing said spring for actuating said contact elements and pendulum means for controlling said last means.

6. An electrical switching device for rendering inoperative the electrical circuit of a vehicle upon a condition of collision or the like, comprising a plurality of electrical contact elements, a spring member electrically independent of said contact elements for actuating said contact elements, a lever, a pivotal support for said lever, means at one end of said lever for engaging and holding said spring under tension, means engaging the other end of said lever for tripping said lever and releasing said spring for actuating said contact elements, pendulum means for controlling said last means and resetting means for resetting said lever after it is tripped.

7. An electrical switching device for rendering inoperative the electrical circuits of a vehicle upon a condition of collision or the like, comprising a plurality of electrical contact elements, a spring member electrically independent of said contact elements for actuating said contact elements, a lever including catch means for holding said spring member in a predetermined position, means associated with said contact elements for engaging said spring member when the latter is released by said catch means, pendulum means for engaging said lever to release said catch means from said spring for actuating said contact and resetting means for resetting said lever after it is released.

8. A switch for effecting changes of the electrical circuits upon vehicles and craft upon a condition of impact, comprising a freely suspended pendulum, supporting means comprising a pair of independent pivots for pivotally supporting said pendulum with two degrees of rotative freedom, a spring urged lever adapted to engage and to damp the movement of said pendulum, contact elements held in normal position under

spring action, a spring urged member normally held in tensioned position by said pendulum and lever and adapted when released upon occurrence of impact to actuate said contact elements 5 to effect desired circuit changes and manually operable resetting means for resetting said lever after it is released.

9. An electrical switching device for rendering inoperative the electrical circuits of a vehicle 10 upon a condition of collision or the like, comprising: a panel member, a pendulum pivotally supported on said panel member, a first lever also pivotally supported on said panel, means attached to said first lever for slidably engaging 15 said pendulum, said first lever having a first latch device, a second lever pivoted with respect to said first lever and having an end engageable with said first latch device of said first lever, a rotatable shaft, a spring attached to said shaft, said second 20 lever having a second latch device, means on said shaft for engaging said second latch device of said second lever when said shaft is rotated against said spring, an electrical contact device, and means for actuating said electrical contact 25 device when said shaft and said levers are released by movement of said pendulum so that said shaft is rotated by the action of said spring.

10. An electrical switching device for rendering inoperative the electrical circuits of a vehicle 30 upon a condition of collision or the like, comprising: a rotatable shaft, a spring attached to said shaft to prevent the rotation of said shaft except with or against the tension of said spring, electrical contacts positioned to be actuated upon 35 the rotation of said shaft, a lever and latch device, means cooperating with said shaft for engaging said lever and latch device when said shaft is turned against the tension of said spring to hold said shaft in this tensioned position, a 40 cam attached to said lever and latch device, and a pendulum having means for engaging said cam to hold said shaft in said tensioned position until a condition of collision or the like disengages said cam from said pendulum means.

45 11. An electrical switching device as set forth in claim 9 including manually operable means for said shaft to reset the switching device after the switching device has been actuated.

12. An electrical switching device as set forth 50 in claim 10 including manually operable means attached to said shaft to reset the switching device after the switching device has been actuated.

13. In a crash actuatable safety switch, a switch mechanism, actuating means for opening 55 and closing said switch mechanism and comprising a spring normally maintaining said switch mechanism in a released position and further comprising latch engaging means, a latch mechanism engageable with said latch engaging means 60 for maintaining said switch mechanism in actuated position, a cam having cooperating means engageable with said latch mechanism for locking the same, and a pendulum having a cam surface engageable with said cam, whereby movement 65 of predetermined amplitude of said pendulum beyond cam engaging position unlocks said latch mechanism and releases said switch mechanism.

14. In a crash actuatable safety switch, a 70 switch mechanism, actuating means for opening and closing said switch mechanism and comprising a spring normally maintaining said switch mechanism in a released position and further comprising latch engaging means, a latch mechanism engageable with said latch engaging means 75

for maintaining said switch mechanism in actuated position, a cam having cooperating means engageable with said latch mechanism for locking the same, a pendulum having a cam surface engageable with said cam, and supporting means 5 comprising a pair of independent pivots for pivotally supporting said pendulum with two degrees of rotative freedom, whereby movement of predetermined amplitude of said pendulum beyond cam engaging position unlocks said latch 10 mechanism and releases said switch mechanism.

15. In a crash actuatable safety switch, a switch mechanism, actuating means for opening and closing said switch mechanism and comprising a spring normally maintaining said switch 15 mechanism in a released position and further comprising latch engaging means, a latch mechanism engageable with said latch engaging means for maintaining said switch mechanism in actuated position, a cam having cooperating means 20 engageable with said latch mechanism for locking the same, a pendulum having a cam surface engageable with said cam, said cam having its periphery engageable with said pendulum cam surface substantially in the form of a circular 25 arc, and a pivot for supporting said pendulum for movement substantially parallel to the plane of said arc, said arc being substantially struck about said pivot as a center, whereby movement of predetermined amplitude of said pendulum beyond 30 cam engaging position unlocks said latch mechanism and releases said switch mechanism.

16. In a crash actuatable safety switch, a switch mechanism, actuating means for opening and closing said switch mechanism and comprising a spring normally maintaining said switch 35 mechanism in a released position and further comprising latch engaging means, a latch mechanism engageable with said latch engaging means for maintaining said switch mechanism in actuated position, a cam having cooperating means 40 engageable with said latch mechanism for locking the same, a pendulum having a cam surface engageable with said cam, said cam having its periphery engageable with said pendulum cam 45 surface in the form of a circular arc, said pendulum cam surface being recessed in a direction substantially perpendicular to the plane of said arc, and a pair of mutually perpendicular cooperating pivots for supporting said pendulum 50 for movement substantially respectively perpendicular and parallel to the plane of said arc, said arc being substantially struck about a center in said pivot about which said pendulum moves parallel to the plane of said arc, whereby movement 55 of predetermined amplitude of said pendulum beyond cam engaging position unlocks said latch mechanism and releases said switch mechanism.

17. In a crash actuatable safety switch, a switch mechanism, actuating means for opening 60 and closing said switch mechanism and comprising a spring normally maintaining said switch mechanism, in a released position and further comprising latch engaging means, a latch mechanism engageable with said latch engaging means 65 for maintaining said switch mechanism in actuated position, a cam having cooperating means engageable with said latch mechanism for locking the same, a pendulum having a cam surface engageable with said cam, said cam having its 70 periphery engageable with said pendulum cam surface in the form of a circular arc, said pendulum cam surface being recessed in a direction substantially perpendicular to the plane of said arc, and a pair of mutually perpendicular cooper- 75

ating pivots for supporting said pendulum for movement substantially respectively perpendicular and parallel to the plane of said arc, said arc being substantially struck about a center in said 5 pivot about which said pendulum moves parallel to the plane of said arc, said pivot about which said pendulum moves perpendicular to the plane of said arc being positioned substantially above

the point where said cam arc meets said cam surface when said pendulum is in normal position, whereby movement of predetermined amplitude of said pendulum beyond cam engaging position unlocks said latch mechanism and releases said switch mechanism. 5

HUBERT MACKENZIE SALMOND.
